UNITED STATES PATENT OFFICE

100,692

DESIGN FOR A LIP STICK CASE

Paul H. Ganz, New York, N. Y.

Application April 3, 1936, Serial No. 61,925

Term of patent 14 years

To all whom it may concern:

Be it known that I, Paul H. Ganz, a citizen of the United States and a resident of the city, county, and State of New York, have invented a new, original, and ornamental Design for a Lipstick Case, of which the following is a specification, reference being had to the accompanying drawing, forming part thereof.

Figure 1 is a side elevational view of a lipstick case, showing my new design;

Figure 2 is a top plan view thereof; and

Figure 3 is a section on the line 3—3 of Figure 1, looking in the direction of the arrows.

In addition to the general effect of the contours resulting from the beads at the top and bottom and the flutings therebetween, I have shown in the drawing as an added feature, a finish or coloration between the raised portions of the flutings and the beads at the top and the bottom of the lipstick case, as distinct from the remaining portions of the case.

I claim:

The ornamental design for a lipstick case, as shown and described.

PAUL H. GANZ.
